S. M. COFFMAN,
ELECTRIC HAIR DRYING DEVICE,
APPLICATION FILED APR. 1, 1919.

1,352,876.

Patented Sept. 14, 1920.

UNITED STATES PATENT OFFICE.

SAMUEL M. COFFMAN, OF KANSAS CITY, MISSOURI, ASSIGNOR TO THE BARBERS ELECTRIC SPECIALTY COMPANY, A CORPORATION OF KANSAS.

ELECTRIC HAIR-DRYING DEVICE.

1,352,876.

Specification of Letters Patent. Patented Sept. 14, 1920.

Application filed April 1, 1919. Serial No. 236,643.

To all whom it may concern:

Be it known that I, SAMUEL M. COFFMAN, a citizen of the United States, residing at Kansas City, in the county of Jackson and 5 State of Missouri, have invented certain new and useful Improvements in Electric Hair-Drying Devices, of which the following is a specification.

My invention relates to hair drying devices and while it may be used to advantage for a variety of purposes, it is intended more particularly for use in barber shops for directing a blast of either relatively hot or relatively cold air against the head for 15 the purpose of drying the hair after a shampoo.

In the accompanying drawing which shows the preferred embodiment of the invention, Figure 1 is a side elevation of the 20 device.

Fig. 2 is a plan view of the device.

Fig. 3 is an inverted plan view of the device.

Fig. 4 is a longitudinal sectional view of 25 the device.

Fig. 5 is a detail inverted cross section on line V—V of Fig. 1.

In carrying out the invention, I employ a chamber 1 having a removable cap 2, so that 30 access may be readily had to the interior of said chamber 1. The cap 2 is provided with a perforated front wall 4 for the passage of air therethrough, and is held in position by a pin and a bayonet-slot 6 and 8, respectively. 35 The rear wall 10 of the chamber 1 is provided with a number of equally spaced openings 12 for the passage of air therethrough. The rear wall 10 is also provided with a tubular handle 14 having a vulcanized rubber 40 or other suitable grip 16, removably held in place by a transverse screw 18.

20 designates a plate fitting against the rear wall 10 and provided with a sleeve 22 rockably mounted upon the handle 14, and 45 having a thumb-piece 23 whereby it may be actuated. The plate 20 is provided with equally spaced openings 24, which register with the openings 12 in the rear wall of the chamber 1 when said plate 20 is rocked to 50 one position. Wire cloth 26 or perforated plates are arranged within the openings 24

to prevent obstructions from being drawn therein by the air blast created by a fan 28 mounted within the chamber 1.

30 designates a plurality of ducts fixed to 55 the plate 20 and alternately arranged with the openings 24, as disclosed on Fig. 3. The outer ends of the ducts 30, like the openings 24, are provided with wire cloth 32 or perforated plates.

The ducts 30 are provided with electric heating coils 34, preferably, connected in series, the first coil in the series being connected to a circuit wire 36 which is connected to a contact 37 adapted to slidably engage a 60 contact 39 connected to a circuit wire 40, while the last coil in the series is connected to a circuit wire 42. The circuit wires are insulated and the free ends of the circuit wires 40 and 42 are connected 65 to a plug (not shown) which may be inserted in the socket of an incandescent lamp, or other device connected to a source of electricity. The contacts 37 and 39 are mounted on a duct 30 and the chamber 1, respectively, 70 and the contact 37 also acts as an indicator to coact with the inscriptions "Cold" and "Hot" on the chamber 1. A guard 43 is fixed to the chamber 1 to prevent the operator's fingers from touching the contacts 75 37 and 39 and receiving a shock when the current is on.

The fan 28 is fixedly mounted upon a shaft 44 journaled in the handle 14 and having a hollow, slotted terminal 46, so that it may 85 be readily connected to a flexible shaft driven by an electric or other suitable motor (not shown). The shaft 44 is provided with a peripheral groove 46 to receive the inner end of the screw 18, whereby said shaft 90 46 is held from moving longitudinally in its bearings.

48 designates a brake member which extends through slots 50 in the sleeve 22 and limits the rocking movement thereof upon 95 the handle 14. Said brake member 48 also extends through openings 52 in the handle 14 and has a transverse opening 54 through which the shaft 44 freely extends. By pressing upon either end of the brake member 100 48 sufficient friction is created between it and the shaft 44 to retard the latter and

thus regulate the speed of the fan 28 and the force of the air current created thereby.

The operation is substantially as follows: When a cold blast of air is desired the plate 5 20 is rocked to adjust the openings 24 in coincidence with the openings 12, so that as the fan rotates it will draw cold air through said openings 24 and 12 and force it out through the perforated front wall 4 of the chamber 10 1. When a hot air blast is desired the plate 20 is rocked to bring the ducts 30 into coincidence with the openings 12, so that as the air is drawn through said ducts by the fan 28 it becomes heated in its passage by contact with the coils 34. If maximum heat is 15 not desired the plate 20 is adjusted until the openings 24 and the ducts 30 both communicate with the openings 12, so that the fan 28 will draw both cold and heated air into the 20 chamber 1 and force it out through the perforated wall 4. As disclosed by Figs. 1 to 3, inclusive, the circuit closer contact 39 is of sufficient length to remain in engagement with the contact 37 until the plate 20 is adjusted to bring the openings 24 fully into 25 coincidence with the openings 12, when said contact 37 passes out of engagement with the companion contact and interrupts the circuit to the coils 34.

30 While I have shown and described the preferred embodiment of the invention, I reserve the right to make such changes in the construction, combination and arrangement of parts as properly fall within the spirit 35 and scope of the claims.

Having thus described my invention, what I claim and desire to secure by Letters Patent, is:

1. In a device of the character described, 40 a chamber arranged for the passage of air therethrough, a handle to the device, a hot air duct adapted to communicate with said chamber to supply the same with heated air, and means for adjusting said duct in and out 45 of communication with the chamber.

2. In a device of the character described, a chamber arranged for the passage of air therethrough, a handle to the device, a hot air duct adapted to communicate with said 50 chamber to supply the same with heated air, and rockable means on the handle for adjusting said duct in and out of communication with the chamber.

3. In a device of the character described, 55 a chamber having a perforated front wall for the passage of air therethrough, a handle to the device, and a plurality of hot air ducts communicating with said chamber to supply the same with heated air and provided with perforated walls at their rear ends.

4. In a device of the character described, a chamber arranged for the passage of air therethrough, a handle to the device, a hot 60 air duct adapted to communicate with said

chamber to supply the same with heated air, electrical heating means in said duct to heat the air therein, and a circuit breaker which is opened to cut off the current to said electrical heating means when the duct is adjusted out of communication with the chamber. 70

5. In a device of the character described, a chamber arranged for the passage of air therethrough, a handle to the device, a hot 75 air duct adapted to communicate with said chamber to supply the same with heated air, electrical heating means in said duct to heat the air therein, a contact on the chamber wall, and a contact on the duct which is 80 thrown into engagement with the first contact when said duct is adjusted into communication with the chamber.

6. In a device of the character described, a chamber arranged for the passage of air 85 therethrough, a handle to the device, hot air ducts spaced equidistant apart and communicating with said chamber to supply the same with heated air, a fan within the chamber to expel the heated air therefrom, and a shaft 90 journaled in the handle carrying said fan. 95

7. In a device of the character described, a chamber arranged for the passage of air therethrough, a handle to the device, hot air ducts spaced equidistant apart and communicating with said chamber to supply the same with heated air, a fan within the chamber to expel the heated air therefrom, a shaft journaled in the handle carrying said fan, and a brake extending loosely through the handle and adapted to frictionally engage said 100 shaft. 105

8. In a device of the character described, a chamber having a perforated front wall and equally-spaced openings in its rear wall 110 for the passage of air therethrough, a plate rockably mounted at the rear of said chamber and having openings which register with the first-mentioned openings when said plate is rocked to one position, ducts fixed to said 115 plate and arranged to communicate with the first-mentioned openings when the plate is rocked to another position, and means for heating the air in said ducts. 120

9. In a device of the character described, 115 a chamber having a perforated front wall and equally-spaced openings in its rear wall for the passage of air therethrough, a plate rockably mounted at the rear of said chamber and having openings which register with the last-mentioned openings when said plate is rocked to one position, ducts fixed to said 120 plate and arranged to communicate with the first-mentioned openings when the plate is rocked to another position, means for heating the air in said ducts, and a handle to the device. 125

10. In a device of the character described, a chamber having a perforated front wall and equally-spaced openings in its rear wall 130

for the passage of air therethrough, a plate rockably mounted at the rear of said chamber and having openings which register with the first-mentioned openings when said plate is rocked to one position, ducts fixed to said plate and arranged to communicate with the first-mentioned openings when the plate is rocked to another position, means for heating the air in said ducts, a handle to said

device, and a fan for creating a current of 10 air through the ducts and the chamber.

In testimony whereof I affix my signature, in the presence of two witnesses.

SAMUEL M. COFFMAN.
